UNITED STATES PATENT OFFICE.

COLUMBUS K. LASSITER AND JULIUS KINDERVATER, OF NEW YORK, N. Y.

CONDENSATION SEPARATOR AND COLLECTOR.

Application filed May 10, 1922. Serial No. 559,952.

To all whom it may concern:

Be it known that we, COLUMBUS K. LASSITER and JULIUS KINDERVATER, citizens of the United States, residing at New York, in 5 the county of New York and State of New York, have invented new and useful Improvements in Condensation Separators and Collectors, of which the following is a specification.

10 This invention relates to condensation separators and collectors for use in the steam supply systems of locomotives for the purpose of separating from the steam passing from the steam generator or boiler to the locomotive cylinders any water of condensation which may be deposited in the interconnecting steam supply passages, or any water which may under certain conditions be drawn or injected into said passages from 20 the water space of the boiler.

For purpose of exemplification, and as disclosing one mode of practical application of the invention, we have herein shown and described the invention as used particularly 25 upon a locomotive of the well-known superheater type, although it is to be understood that the invention is not limited thereto, as it may also be used upon locomotives of the saturated steam type.

30 As is well known to those versed in the art, considerable expense and inconvenience is experienced from water accumulating in the dry and superheater pipes of a locomotive of the superheater type when the locomotive has been standing for some time. It is assumed that leaky throttle valves are primarily the cause of this condensation, which is more pronounced the longer the locomotive stands, and usually results in extensive damage to the cylinders. When the locomotive is standing the damper is supposed to be in a closed position, cutting off all draught through the large flues, thus avoiding the possibility of burned superheater units. The 35 temperature being considerably lowered when the draught is thus cut off, any leakage through the throttle will condense in the superheater units and the longer the locomotive stands the greater the condensation.

40 Upon opening the throttle the accumulation of water is forced into the cylinders, and the piston on making the maximum end stroke pockets the water, causing the breakage of cylinders.

45 It is also well known that, through sur-

ing or other causes, water is sometimes injected into the steam passages through the open throttle from the water space of the boiler when the locomotive is in operation, which may occur in a locomotive of either 60 type mentioned, with consequent liability of injury to the cylinders.

One object of our invention is to provide a novel and improved construction of separator, formed on and as part of a steam admission pipe, and having a separating action of a character to ensure a maximum degree of separation of the water from the steam, whereby only reasonably dry steam will be allowed to enter the cylinder under any and 70 all conditions of service, thus obviating liability of damage to the cylinders.

Another object of the invention is to provide means for heating and regenerating into steam for service use all or a large proportion of the separated water of condensation, thus ensuring economy of operation and wholly or largely preventing water waste.

Still another object of the invention is to 80 provide a novel pressure-controlled automatic relief-valve for governing the flow of the separated water of condensation from the separator to the aforesaid heating means for its conversion into steam and return to the 85 steam line, or its discharge from the separator to the exterior of the locomotive as waste water, according to different phases or conditions of service in the operation of the 90 engine.

Still another object of the invention is to provide a condensation separator and collector which is adapted for use with equal efficiency upon a locomotive of the superheated steam type or a locomotive of the 95 saturated steam type.

In the accompanying drawings, in which we have shown the application of the invention to a locomotive of the superheated steam type,

Figure 1 is a view, partly in side elevation and partly in vertical longitudinal section, of the forward portion of a locomotive equipped with our invention.

Figure 2 is a vertical transverse section 105 through the smoke-box looking from the front rearwardly toward the steam admission pipes and front flue sheet, and showing one of the steam admission pipes in elevation and the other partially in section.

110

Figure 3 is a detail horizontal section on the line 3—3 of Figure 1.

Figures 4, 5 and 6 are, respectively, a top plan view, a side elevation, and a cross-section, of a preferred form of water heating and steam generating coil constituting a part of our invention.

Figure 7 is a fragmentary view in side elevation looking from the exterior toward one side of the smoke-box.

Figure 8 is a diagrammatic sectional view illustrating the separating action during the course of steam supply.

Figure 9 is a generally similar view illustrating the action of the automatic relief-action when the steam flow is cut off.

Referring now more particularly to the drawings, 1 designates the boiler shell, 2 the front flue sheet, 3 the smoke-box, 4 the smoke-stack, 5 the dry-pipe, 6 the header, and 7 the smoke-flues or fire-tubes of a locomotive of the character described. The header 6 is arranged, as usual, in the smoke-box 3 and is provided with a steam-inlet 8 connected with the dry-pipe 5, and with steam-outlets 9 connected with the steam-admission pipes 10 leading therefrom to the engine cylinders 11. 12 are the superheater tubes or units, of which any suitable number may be employed, arranged within a corresponding number of the flues 7, the inlet and outlet ends (generally indicated at 13) of which units 12 communicate with the saturated and superheated steam chambers of the header 6. The parts above-described are shown as essential in order to illustrate the application of the invention, the damper and other parts commonly employed being omitted as unessential to a full and complete disclosure of the invention.

In carrying our invention into practice, we provide means arranged in the line of flow of the steam from the steam boiler or generator to the steam chest of each cylinder for separating and converting into steam or discharging to the exterior of the locomotive, any water of condensation, or other water, which may be flowing toward the cylinder with the steam. The means provided for this purpose preferably comprises a separator and collector arranged within each steam admission pipe 10 and forming a component part thereof. The separator and collector arranged within each pipe 10 is generally indicated at 14 and is preferably cast with the pipe and formed as an expanded portion thereof. As shown, said separator and collector is arranged in each pipe 10 between the goose-necked inlet end 15 thereof, which connects with the associated header outlet 9, and the outlet end 16 thereof, which connects with the associated cylinder 11. The body of the separator is constructed to provide a longitudinal steam chamber 17 and a longitudi-

dinal separating chamber 18, the latter terminating at its lower end in a water collecting trap or pocket 19. The chamber 18 is in direct communication at its restricted upper end or throat 20 with the inlet end 15, which throat communicates with the upper portion of the chamber 17 through a lateral or cross passage 21. Below this passage 21 the two chambers 17 and 18 are separated and closed against communication with each other by a partition wall 22. This partition wall 22 has its upper end portion arranged to form the bottom of the passage 21, and said end portion is curved or inclined in an upward and forward direction toward the chamber 17 to form a deflector-baffle 23. Between this deflector-baffle 23 and the downwardly and forwardly curved wall 24, extending from the inlet 15 to the front wall of chamber 17, and which forms a top wall common to both chambers 17 and 18, is arranged a series of baffles, comprising one or more baffle plates 25, directly arranged within the passage 21, and a top deflector-baffle 26 integral with the wall 24. The baffles 25 are preferably straight and parallel with each other and with the baffles 23 and 26 and incline at such an angle to the vertical plane of the passage 21, as to form, with the deflections 23 and 26, a series of superposed overlapping baffle plates or walls which prevent the direct horizontal flow of steam and water from the top portion of chamber 18 to the top portion of chamber 17, and which separate the cross passage 21 into a series of relatively smaller straight and parallel cross passages. These smaller cross passages are, as shown, inclined upwardly and forwardly between the two chambers 18 and 17, in a direction toward the forward convexly-curved portion 27 of wall 24 which directly forms the top of chamber 17, thus causing the steam entering through the throat to flow well down into the chamber 18 before it can flow through the passage 21 into the chamber 17. In addition, the deflector 26, which is curved on a slight arc in a direction downwardly and rearwardly toward the rear wall of chamber 18, tends to deflect the fluid entering through the throat 20, in such direction, i. e., in a direction away from the passage 21. As a result, the direct flow of steam from the throat 20 to the chamber 17 will be prevented, and the steam will be caused to pass an appreciable distance down into the chamber 18 before it can flow upwardly therefrom into the top of the chamber 17. The purpose of this is to prevent the direct, immediate and forceful jetting of portions of water, under pressure of the steam, or direct flow of steam impregnated with free moisture, through the passage 21, and to secure a reduction of velocity of the

steam and its impingement against the baffles and wall surfaces for a sufficient, though brief, period of time to effect a very desirable and efficient physical separation of the moisture from the steam. At the same time a plurality of superposed inclined passages, lying in a common vertical plane, are formed which allow the steam to flow quickly and directly from one chamber to the other, and a Venetian-blind type of separator, composed of vane-like surfaces, is provided to ensure the rapid and efficient separation of the greater proportion of even the smallest particles of free moisture from the steam and the deflection of such moisture into the chamber 18.

From the foregoing it will be understood that the steam passing from the outlet 9 of the header 6 with any water of condensation, or other water which may be present therewith, into the inlet end 15 of the pipe 10, will flow downward into the throat 20 of said separator and collector, the steam passing through the spaces between the baffles 23, 25 and 26 into the chamber 17, while the water will flow either directly downward into the chamber 18 or strike against the baffles and be conducted thereby down into said chamber 18. As a result the steam in a reasonably dry state will flow through the outlet 16 of the steam admission pipe to the steam chest of the cylinder, while the water will be retained and collected in the pocket or trap 19. By this means the passage of any material or dangerous quantity of water to the cylinder will be prevented and liability of damage to the cylinder obviated.

It will be observed that in our separator, constructed as above-described, the separating chamber (water chamber) 18 is disposed in rear of the steam chamber 17 in the direction of steam flow, the device differing in this respect from prior separators of generally similar type, in which the water chamber is arranged in advance of the steam chamber, causing the steam to be checked considerably in its passage and to reverse its direction of motion and take a course of flow from the front water chamber through the cross passage into the rear steam chamber. Our purpose in so arranging the two chambers 17 and 18 in our device is to overcome certain objections incident to other separators in which the chambers are arranged in reverse order thereto, and to secure certain advantages in function and result, as follows:

First. In a separator in which the steam flows into a front separating (water) chamber, and is compelled to reverse its course of travel in order to pass into a rear steam chamber, an increased degree of agitation of the steam occurs. This unduly checks the flow of the steam and results in

the agitation of the water in the water compartment, interfering in a large measure with the deposit of moisture, as a result of which portions of the moisture are carried over with the steam into the steam chamber 70 and pass therewith to the cylinder. Our construction overcomes this objection, as the travel of the steam is along its natural course and the only agitation produced is that caused by the steam striking the baffles, 75 which is but slight and not sufficient to seriously obstruct its flow, and is moreover beneficial in promoting physical separation of the steam and water by impingement against the baffles. 80

Second. In separators of this type, where the steam and water enter through a restricted goose-necked inlet at some considerable velocity, the tendency of the fluid column, in discharging from a narrow orifice into a chamber of relatively larger size, is to take a backward course by reaction, in which it dashes against the rear wall of the chamber which it enters. The admission of the fluid column from a goose-necked orifice 25 into a front water chamber, connected at its top by a cross passage with a rear steam chamber, is therefore productive of a serious objection in that a quantity of the water, under force of the steam pressure, is liable 90 to be injected through the cross passage into the steam chamber. This is particularly liable to occur when the water, as sometimes happens, is in some considerable quantity, and the condition is aggravated by the use 95 of an unprotected cross passage, i. e., a fully-open passage unguarded by baffles or other barriers. Our construction effectually overcomes this objection and secures increased separating efficiency, inasmuch as the dash- 100 ing of the water by reaction against the rear wall of the chamber 18 facilitates its separation from the steam and the baffles guard the passage 21 against the entrance of any material amount of water into chamber 17. 110 Furthermore, the steam and water take their normal courses of flow, according to their respective specific gravities, the steam flowing without substantial impedance into the steam chamber, while the water, owing to its greater specific gravity, tends to fall directly into the pocket 19 and any moisture carried by the steam will be arrested by the baffles and trickle down the wall surfaces into the pocket 19. 115

Third. The described disposition of the water chamber provides for keeping the water therein at a high temperature to facilitate its conversion into steam, a material advantage when it is desired to reconvert the water of condensation into steam for water conservation. 120

We provide means for taking care of the water of condensation collected in the trap 19, such means serving to convert the major 125 130

portion of the water into steam and to conduct such steam to the steam line for use, and to discharge any small quantity of water not so used as waste upon the exterior of the locomotive. As shown, a heating (steam generating) coil 28 is employed, which is disposed in one of the fire-tubes 7 so as to be heated by the products of combustion passing through it. This coil may be similar in form and construction to any ordinary four-pipe superheater tube or unit. The water inlet end 29 of said coil communicates with the trap 19 of the water chamber 18, while the steam delivery end 30 of the coil communicates with the same chamber 18 at a higher level than the coil end 29, preferably at an elevation above the highest water level. Arranged in rear of the base of chamber 18 is an automatic relief-valve comprising a casing 31 having at its top a lateral inlet 32 communicating with the water trap 19, and having at its bottom an outlet 33. Between said inlet and outlet is a valve seat 34, against which is adapted to close a vertically movable valve 35, normally held open and in raised position above the valve seat by a spring 36. This valve is so arranged as to close under fluid pressure against its top face exceeding the expansive force of its opening spring 36. A drain pipe 37 leads from the outlet 33 through the smoke-box shell for the discharge of any waste water at one side of and upon the exterior of the locomotive.

35 The operation of this part of our invention is as follows:

When the locomotive throttle valve is open, the condensed water is injected, as previously described, into the water chamber 18 of the combined steam pipe and separator. The pressure being on top of the automatic relief-valve 35, said valve is closed against the resistance of spring 36, and all the condensed water which may be in the superheaters or the dry pipe is, therefore, injected into the water chamber 18. As long as the throttle is open, this water is circulated through the coil 28 and is generated into steam, the steam being liberated at a point slightly above the maximum water level in the chamber 18 and passing therefrom into the steam chamber 17. In the event that the throttle valve is closed, and any water remains in the water chamber 18, 55 the valve 35, being relieved of steam pressure, will be opened by spring 36, and the water will drain from the water chamber outward through pipe 37.

This device provides for generation into steam of the major portion of the water of condensation, which would ordinarily be allowed to go to waste. It will be observed that the valve is entirely automatic in character and, in the arrangement disclosed, is arranged within the smoke-box 3 and there-

fore enclosed and protected from liability of casual injury. In practice, this valve may be disposed adjacent to and in line with an opening 38 in the side of the smoke-box, to permit quick and convenient access thereto in case of repairs, this opening 38 being normally closed by a removable cover plate 39.

In practice, as stated, the separator and collector 14 is preferably cast with and as a component part of the steam admission pipe 10, but obviously it may be formed separately from the inlet and outlet ends of said pipe and bolted or otherwise suitably coupled thereto. Also, as stated, while the invention is particularly shown and described herein as applied to a locomotive of the superheated steam type, it may be employed in an obvious manner and with equal efficiency in connection with a locomotive of the saturated steam type. Except when particularly set forth in the appended claims, therefore, we do not limit the invention to specific use in connection with either of these types of locomotives.

Having thus fully described our invention, we claim:—

1. In a locomotive, the combination of a steam generator; a cylinder; a steam supply pipe connecting the steam generator and the cylinder; and a separator disposed in said pipe and comprising a casing having a rear vertically arranged separating chamber communicating at its upper end with the pipe inlet and having a water collecting trap at its lower end, a front vertically arranged steam chamber communicating at its lower end with the pipe outlet, a curved upper wall extending forwardly and downwardly from the top of said inlet to the front wall of the steam chamber and forming a top wall common to both chambers, a vertical partition between said chambers terminating at its upper edge below said curved top wall and forming an intervening main cross passage in vertical alignment therewith for the forward flow of steam from the top of the separating chamber to the top of the steam chamber, and a vertical series of spaced baffle plates arranged in superposed and lapping relation in said main passage and subdividing the same into a plurality of relatively smaller passages inclined at an upward and forward angle to the vertical plane of said main passage.

2. In a locomotive, the combination of a steam generator; a cylinder; a steam supply pipe connecting the steam generator and the cylinder; and a separator disposed in said pipe and comprising a casing having a goose-necked inlet end and an outlet end, a rear vertically arranged separating chamber communicating at its upper end through a throat with the pipe inlet and having a water trap at its lower end, a front verti-

cally arranged steam chamber communicating at its lower end with the pipe outlet, a curved upper wall extending forwardly and downwardly from the top of said inlet to 5 the front wall of the steam chamber and forming a top wall common to said chambers, a vertical partition between said chambers terminating at its upper edge below said curved top wall and forming a transverse 10 passage in vertical alinement with said partition for the forward flow of steam from the top of the separating chamber to the top of the steam chamber, a downwardly and rearwardly inclined deflector-baffle on the curved 15 top wall, an upwardly and forwardly inclined deflector-baffle at the upper edge of the partition, and inclined baffle plates in said passage between said deflector-baffles.

3. In a locomotive, the combination of a 20 steam generator, a cylinder, a steam pipe for supplying steam from the generator to the cylinder, a separator in said steam pipe having a rear separating chamber and a front steam chamber, said rear separating 25 chamber being in communication at its upper end with the pipe inlet and provided at its lower end with a valved outlet, and said front steam chamber being in communication at its upper end through a transverse passage 30 with said separating chamber and in communication at its lower end with the cylinder, and a vertical series of spaced and superposed and lapping baffle plates guarding said passage, said baffle plates being inclined at an upward and forward angle to the 35 vertical plane of the passage.

4. In a locomotive, the combination of a steam generator, a cylinder, a steam supply pipe connecting the steam generator and the 40 cylinder, said pipe having an inlet end and a goose-necked outlet end, and a separator disposed in said pipe between said ends, said separator comprising a vertical steam chamber upon the forward portion of the pipe 45 communicating at its lower end with the outlet end of the pipe, a vertical separating chamber upon the rear portion of the pipe and having a water trap at its lower end and communicating at its upper end with the inlet end of the pipe, said chambers being connected at their upper ends by a cross passage for the forward flow of steam from the separating chamber to the steam chamber, a downwardly and forwardly curved wall 55 connecting the top of the goose-necked inlet with the front wall of the steam chamber and forming a top wall common to both chambers, said top wall overlying said cross- 60 passage, means for discharging collected water from the trap, and a vertical series of spaced baffle plates guarding said cross passage inclined at an upward and forward angle to the vertical plane of said passage.

5. In a locomotive, the combination of a 65 steam generator, a cylinder, a steam supply

pipe connecting the steam generator and the cylinder, and a separator disposed in said pipe between the inlet and exit ends thereof, said separator having a forward steam chamber communicating at its lower end 70 with the exit end of the pipe, a rear separating chamber having at its lower end a water trap and communicating at its upper end with the inlet end of the pipe, said chambers communicating at their upper ends through 75 a transverse passage, and a series of baffles guarding said passage and comprising an upper baffle member inclined downwardly and rearwardly toward the rear wall of the separating chamber, a lower baffle member 80 inclined upwardly and forwardly toward the front wall of the steam chamber, and one or more intermediate baffle members inclined at an angle to the vertical plane of the passage.

6. In a locomotive, the combination of a steam generator, a cylinder, a steam pipe, a separator disposed in said pipe and having an inlet chamber and an outlet chamber, means connected with the lower portion 90 of the inlet chamber for receiving the water deposited therein, means for heating said receiving means, and a connection from said receiving means to the upper portion of said inlet chamber.

7. In a locomotive, the combination of a steam generator, a cylinder, a steam pipe, a separator disposed in said pipe and having an inlet chamber and an outlet chamber, and a steam generating coil having an inlet 100 end connected with the lower portion of said inlet chamber for receiving the water deposited therein and an outlet end connected with the upper portion of said inlet chamber for delivering the generated steam 105 thereto.

8. In a locomotive, the combination of a steam generator, a cylinder, a steam pipe, a separator arranged in said pipe and having an inlet chamber and an outlet chamber, 110 baffling means between said chambers, and a steam generating coil having an inlet end connected with the lower portion of said inlet chamber for receiving the water deposited therein and an outlet end connected 115 with the upper portion of said inlet chamber for delivering the generated steam thereto.

9. In a locomotive, the combination of a steam generator, a cylinder, a steam pipe 120 having a water separator disposed therein, said separator including a separating chamber having a waste outlet, and a steam chamber, a heating coil having its inlet end communicating with the lower portion of the 125 separating chamber and its delivery end communicating with the upper portion of said chamber, and a valve operating to close said waste outlet when subjected to steam pressure in the separating chamber and to 130

open the outlet when relieved of such pressure.

10. In a locomotive, the combination of a steam generator, a cylinder, a steam pipe, 5 a water separator disposed in said pipe and having a separating chamber and a steam chamber, said separating chamber being provided with a waste outlet, a heating coil disposed so as to be heated by products of combustion passing through a fire-tube, said coil having an inlet end disposed to receive water from said separator and an outlet end disposed to deliver generated steam thereto, and a valve for closing the waste outlet in 10 the presence of steam pressure in the steam line and to open said outlet when such pressure ceases.

11. In a locomotive, the combination of a steam generator, a cylinder, a steam pipe 20 connecting the generator with the cylinder, a separator disposed in said pipe and having a separating chamber and a steam chamber, means for withdrawing water of condensation from the separating chamber and 25 generating it into steam and returning it to the steam line for use, and a waste valve for maintaining water in the water chamber for passage to said steam generating means when subjected to steam pressure in 30 the steam line and operating on a removal

of steam pressure for venting the water from said water chamber.

12. In a locomotive, the combination of a steam generator, a cylinder, a steam pipe connecting the generator and cylinder, a 35 separator in said pipe comprising a steam chamber upon the forward portion of the pipe communicating at its lower end with the delivery end of the pipe, and a separating chamber upon the rear portion of the pipe having a water trap at its lower end and communicating at its upper end with the inlet end of said pipe, said chambers being in communication at their upper ends through a transverse passage, baffling means in said passage, a heating coil 40 communicating at its inlet end with the waste trap of the separating chamber and at its delivery end with the top portion of said chamber, and a valve controlling the 45 waste outlet from the water trap, said valve being adapted to automatically open in the absence of steam pressure within the separator and to be closed under pressure therein to retain water in the water chamber for 50 passage to said coil.

In testimony whereof we affix our signatures.

COLUMBUS K. LASSITER
JULIUS KINDERVATER.
